GUN FOR DISPENSING PLASTIC MATERIAL

Clem A. Strohmeier, Cleveland, Ohio, assignor of
one-third to Arnold J. Rose and two-thirds to
Melvin Rose

Application August 28, 1948, Serial No. 46,588.

7 Claims. (Cl. 74—169)

1

My invention relates to guns for dispensing plastic material, such as caulking guns and the like.

An object of my invention is to provide an improved arrangement of the operating parts of a plastic dispensing gun facilitating and improving the use and operation of the gun.

Another object is the provision of improved operating mechanisms for a gun in which the operating levers are disposed for a maximum of universal use and for convenience of the operator.

Another object is the provision of an improved gun having operating levers and a release lever so arranged and associated that the operator may, with a minimum of effort and movement, go from manipulating the operating levers to operating the release lever, and vice versa.

Another object is the provision of an improved gun for dispensing plastic material having parts arranged and associated to provide for easy and ready manipulation of the gun and for its universal use in practice.

Another object is the provision of an improved structure facilitating the fabrication and assembly of the operating parts in a gun.

Another object is the provision of an improved gun structure which is economical to manufacture and efficient in use.

Another object is the provision of an improved gun for dispensing plastic material having a structure and operation not heretofore known and producing results not heretofore obtainable.

Another object is the provision of an improved structure facilitating the quick, economical and ready assembly and disassembly of the operating mechanism of a gun of this character.

Other objects and a fuller understanding of the invention may be had by referring to the following description and claims, taken in conjunction with the accompanying drawings, in which:

Figure 1 is a side view of a plastic dispensing gun embodying the preferred form of my invention;

Figure 2 is an enlarged sectional view of the right-hand end of my gun shown in Figure 1, and is a section taken through line 2—2 of Figure 1, the parts shown in Figure 2 being removed from the cylinder or barrel of the gun for simplicity of illustration;

Figure 3 is an end view of the parts shown in Figure 2 looking in the direction of the arrow 3—3 of Figure 2;

Figure 4 is a cross-sectional view of the parts shown in Figure 2 and looking in the direction of the arrows 4—4 of Figure 2;

2

Figure 5 is a longitudinal sectional view of the parts shown in Figure 2 looking in the direction of the arrows, and taken along the line of, 5—5 of Figure 2;

Figure 6 is a separate view of the cap member used for mounting the operating parts to the cylinder of my gun;

Figure 7 is a view of the spacer block used in the mounting of the operating parts on my gun;

Figure 8 is a detailed view showing the notched end of one of the support members used for supporting the operating levers of my device; and

Figure 9 is a detailed view showing the notched end of a support member for supporting the detent plate and releasing handle of my gun.

My plastic dispensing gun embodies a cylinder or barrel 11 of the usual type and which is used for receiving the plastic material, such as caulking material or grease, dispensed from the gun.

A nozzle 12 of usual form is mounted on the forward end of cylinder 11, whereby plastic material contained in the cylinder 11 is ejected out through the open end of nozzle 12 upon operation of the gun. The forward end of the cylinder 11 is removable to provide for loading the gun with plastic material. A cartridge of plastic material may be inserted into the front end of the cylinder or plastic material may be drawn or sucked into the gun by insertion of the nozzle into a container of the material by reversing the operation of the piston. The piston 13 is mounted within the cylinder 11 to reciprocate therein in the usual manner. A piston rod 14 connected to the piston 13 extends axially of the cylinder 11 and rearwardly from the rearward end of the cylinder 11.

The piston rod 14 is advanced forwardly in steps or increments by a feeding plate 20. The feeding plate 20 is of the angle-friction type, in that the plate 20 has an opening therein slightly larger than the cross section of the rod 14. In the preferred embodiment the rod 14 is square in cross section and the opening in feeding plate 20 is likewise square. The fit of rod 14 in the opening in plate 20 is such that when plate 20 is at right angles to the axis of rod 14, the rod 14 may freely slide through the opening in the plate. Upon tilting of plate 20 out of this right angle position relative to rod 14, the edge of the plate 20 on the sides of the opening therein bite into and frictionally engage the surface of the rod 14, so that forward movement of the plate 20, that is, toward the left of the gun in Figure 1, positively advances the rod 14 and moves the piston 13 forwardly to eject plastic material from the gun. As seen in Figure 2, feeding plate 20 extends to one

side of rod 14 more than the other side to provide an engaging surface for the tilting of plate 20.

To recurrently tilt plate 20 at an angle and to move it forwardly toward the cylinder 11, there is provided a pair of crank arm levers 15 and 16. These crank arm levers 15 and 16 each have an outer arm forming a handle movable toward and away from the outer arm forming the handle of the other lever. The handle portions of levers 15 and 16 are dimensioned so that the hand of the operator may grip both of them and by squeezing his hand cause the levers to move relative to each other. The inner arms of levers 15 and 16 are directed toward each other and are pivotally interconnected through a collar 18 and bolts 19. Bolts 19 extend through holes provided in the overlapping inner arms of the levers and are threadably engaged in a collar 18. The collar 18 is carried in a sliding fit on the piston rod 14 so as to be reciprocally movable relative to the cylinder. Thus the levers 15 and 16 are pivotally interconnected and are connected to the collar 18. The crank arm lever 16 at the end of its inner arm has a crosspiece or connecting portion 17. This crosspiece 17 is disposed to move against the outer edge of feeding plate 20 so as to tilt the feeding plate 20 and to move it forwardly upon movement of the handles of levers 15 and 16 toward each other. As the handle portions of levers 15 and 16 are moved toward each other, the inner arms of levers 15 and 16 swing forwardly toward the cylinder. Upon this forward movement of the inner arms, portion 17 tilts the feeding plate into gripping engagement with rod 14, and the collar 18 together with portion 17 advance the feeding plate forwardly and thus move the rod 14 forwardly to advance the piston 13.

Fulcrum support is provided to the respective levers 15 and 16 by means of support members 22 and 23. A pivot connection 24 is provided for connecting support member 22 to lever 15, and a pivot connection 25 is provided for connecting lever 16 to support member 23. Pivot connections 24 and 25 are simply provided by piercing holes at the location where the inner arms and outer arms of the levers meet, and by looping the metal straps of which support members 22 and 23 are comprised through these openings, as shown in the drawing. Support members 22 and 23 are each made up of a strip of metal bent back upon itself and having a loop extending through the openings at the location of the fulcrum for each lever. Inasmuch as the inner arms of the levers 15 and 16 are pivotally interconnected, the fulcrum supports of the levers must be able to move laterally outward, that is, away from rod 14, when the handles of levers 15 and 16 are gripped and moved toward each other. In the preferred embodiment of my invention this lateral displacement of the fulcrum of the crank arm levers is provided by the support members 22 and 23 and pivot connections 24 and 25. Support members 22 and 23, being made of strips of metal, are adapted to flex so as to resiliently spread apart when the handles are moved toward each other. Also the loose fit of the parts at the pivot connections 24 and 25 permits a small give or lateral displacement. As the pivot connections 24 and 25 are positioned at a distance from the rear end of the cylinder, there is room for this flexing of the support members and for the required lateral movement of the fulcrum support provided to the crank arm levers 15 and 16.

Means for anchoring the support members 22

and 23 to the cylinder 11 is provided by a cap member 33 which is threadably engaged to the rear end of the cylinder 11. The threaded cap member 33 has a central opening slightly larger than the cross section of rod 14, so as to permit the rod 14 to slide through the cap member. On diametrically opposite sides of the central opening there are two T-shaped openings 26 and 27 extending through the wall of the cap member. Openings 26 and 27 are arranged so that the stem portion of each respective T-shaped opening is directed radially outward and the broad or base portions of each opening are directed toward each other.

The inner or forward ends of support members 22 and 23 are notched to provide a T-shaped end on each of the support members 22 and 23. The shape of the forward end of support member 22 is shown in Figure 8. The forward end of support member 23 is similar to that shown in Figure 8. The shapes of the forward ends of support members 22 and 23 are complementary to T-shaped openings 26 and 27, in that the broad ends of members 22 and 23 may be moved longitudinally through the broad or wide portions of the T-shaped openings 26 and 27. The narrow neck of the notched ends of members 22 and 23 is adapted to fit in the stem or narrow portion of openings 26 and 27. Thus by inserting members 22 and 23 into the broad or base portion of T-shaped openings 26 and 27 to where the neck or narrow portion of members 22 and 23 are aligned with the stem or narrow portions of openings 26 and 27 and the outward radial displacement of members 22 and 23, there is provided a locking of support members 22 and 23 to cap member 33. To hold the support members 22 and 23 radially outward in interlocked engagement with the cap member 33, a spacer disk 28 is provided. This spacer disk 28 has a central opening slightly larger than the cross-sectional dimension of rod 14 and permits the rod 14 to move through the central opening. The spacer disk 28 is dimensioned to fit between the support members 22 and 23 next adjacent to, and rearwardly of, the cap member 33, and to hold the support members 22 and 23 out in interlocked position, thereby anchoring the support members 22 and 23 to cap member 33.

A resilient coil spring 21 is positioned on rod 14 intermediate of the spacer disk 28 and the feeding plate 20, whereby the feeding plate 20 is resiliently urged rearwardly and in a plane at right angles to the axis of rod 14 and thus in a position whereby the feeding plate 20 does not grip the rod 14 and relative movement between feeding plate 20 and rod 14 is provided. Operation of levers 15 and 16 by inward movement of the handle overcomes the resiliency of spring 21 and provides for the tilting or cocking of feeding plate 20 into gripping engagement with rod 14, and for the forward advancement of rod 14 by the forwardly moving feeding plate 20.

To provide for the retention of the gain made by the piston rod 14 in its step-by-step forward movements, a detent plate 29 is provided. Detent plate 29 is positioned rearwardly of the feeding plate 20 and extends transversely of rod 14 intermediate the handles of operating crank arm levers 15 and 16. The detent plate 29 is provided with an opening complementary to, and slightly larger than, the cross section of rod 14. When detent plate 29 is substantially at right angles to rod 14, rod 14 may freely slide through the opening in the detent plate. Upon swinging of detent

Means for anchoring the support members 22

plate backwardly from this right angle position to a tilted or cocked position, the edges of the opening of detent plate 29 grip and frictionally engage the surface of rod 14 to prevent its rearward movement.

A support member 30 is provided for detent plate 29, and a pivot connection 31 is provided whereby the detent plate 29 is pivotally connected to the rearward end of support member 30 to permit the detent plate to swing from its right angle position to its tilted or cocked position. The relationship of the detent plate 29 to the rod 14 is such that upon forward movement of the rod 14 by action of the feeding plate 20, any frictional engagement between rod 14 and detent plate 29 causes the detent plate 29 to move to its right angle or non-gripping position. However, any rearward movement of rod 14 when detent plate 29 is free to swing on pivot connection 31 provides a frictional engagement between the detent plate and rod and a locking of the rod 14 against rearward movement.

At the outer or free end of the detent plate 29 a handle 32 is provided. This handle 32 is preferably made of the same piece of metal as detent plate 29 and is formed by bending the piece of metal at an angle, whereby handle 32 is at right angles to detent plate 29. Handle 32 is a release handle, in that radial inward pressure on the end of handle 32 swings detent plate 29 to its right angle or non-gripping position and hence out of engagement with rod 14. Upon release of handle 32, detent plate 29 is free to swing on pivot 31 and to perform its detent function. When it is desired to withdraw the piston 13 to its rearward position, the detent plate 29 is released and put in non-operating condition by moving inwardly the handle 32. After release of the rod by the detent the rearward end of rod 14 may be grasped and pulled backwardly relative to the cylinder 11, thus retracting the piston 13. The piston 13 is thus retracted when the cylinder 11 is to be recharged with plastic material such as caulking material or grease.

The support member 30 for detent plate 29 is also anchored to and carried by cap member 33, as were support members 22 and 23 of the operating levers. The T-shaped opening 34 is provided in cap member 33 and the notched end of support member 30, as shown in Figure 9, is adapted to complementarily engage and lock in the opening 34. The spacer disk 38 is dimensioned to have its outer peripheral boundary overlap the large broad portion of opening 34 as it does in respect to openings 26 and 27, and to lock the support member 30 radially outward in interlocked engagement with cap member 33.

It is to be noted that release handle 32 extends forwardly and intermediate the handle to a convenient position for manipulation of the release handle by the operator gripping the operating levers 15 and 16. In this convenient location the thumb of the operator may readily press the release handle 32 downwardly to releasing position while his hand is still gripping the operating levers. Also, the release handle 32 is positioned adjacent the rear end of the cylinder in a convenient position for clasping the rear of the cylinder and the release handle 32 in one hand, while the other hand grasps the rear end of the piston rod 14 for rearward movement of the piston rod upon retraction of the piston 13, as during the loading of the gun.

A small coil spring 35 is positioned around the rod 14 in a loose fit and intermediate the collar

18 and the detent plate 29 for resiliently urging the detent plate rearwardly in a cocked or tilted position, whereby the detent plate holds the rod 14 against rearward movement unless, and until, the release handle 32 overcomes the resilient action of spring 35 to swing the detent plate 29 towards its right angle or non-gripping position.

To limit the outward movement of the handles provided by the outer arms of levers 15 and 16

10 for the most convenient grasping of the handles by the operator's hand, a spacer block 36 loosely mounted on the rod 14 is positioned between spring 35 and the detent plate 29, as illustrated in the drawing. The detent plate 29 in its rearward position provides an abutment for the spacer block 36, which in turn provides an abutment for the rear end of spring 35. The arrangement is such that the collar 18 is urged forwardly relative to the detent plate 29. This tends to keep the handles of the lever 15 and 16 from spreading apart too far for convenient grasping by the hand. The tensions of coil springs 21 and 35 are so balanced relative to each other that the collar 18 and feeding plate 20 are normally held in such a position that the feeding plate 20 is held at a right angle to rod 14 or non-gripping position when the operating levers are in their normal spread-apart position, such as shown in Figure 2.

30 The disposition of the levers 15 and 16 and their arrangement relative to the rod 14 provides for a convenient and easy use of the gun. The gun may be readily operated with either hand, may be turned, twisted and swung around by the operator in use, and easily manipulated in a manner not heretofore obtainable. The limitations in use of guns having a trigger or operating lever disposed at right angles to the piston rod are not present in the arrangement and structure of my gun. There are many advantages in use by reason of the arrangement and disposition of the parts which will be apparent to those knowing the problems of using such guns in everyday practice.

45 My structure also lends itself to quick, ready and economical assembly in the fabrication of the gun. It is to be noted that the support members 22, 23 and 30 are quickly and easily anchored to the cap member 33 without the use of welding, threaded bolts and the like. The parts may be quickly assembled and disassembled with a minimum of effort, and parts may be replaced independently of other parts to be retained.

To assemble the operating parts of my gun,

55 the piston rod 14 is used as the core or fixture upon which the several parts are assembled. Prior to the threadable engagement of the piston rod 14 to the piston 13, and prior to the insertion of the rod 14 in the cylinder 11, the several parts carried on rod 14 are slid over the forward end of the rod 14 onto the rod in their proper sequence. The detent plate 29, the spacer collar 36, the spring 35, the collar 18, the feeding plate 20, the spring 21, the spacer disk 28, and cap member 33 are arranged on the rod 14 in proper order. The levers 15 and 16, pivotally connected to support members 22 and 23, are placed in position, and bolts 19, pivotally connect the levers together and to the collar 18. 60 The support member 30, pivotally connected to detent plate 29, is aligned along with support members 22 and 23 parallel to the axis of the cylinder. Spring 21 is compressed to permit the spacer disk 28 to be manually moved rearwardly and support members 22 and 23 are positioned in

75

respective openings 26 and 27, and at the same time support member 30 is positioned in opening 34. The support members 22, 23 and 30 are moved radially outward and the disk 28 is moved forwardly against the cap member 33 and held in position by spring 21. After this assembly of the operating parts to cap member 33, the piston 13 is threadably engaged to the forward end of the rod 14. The piston 13 and forward end of 14 are then inserted in the open end of cylinder 11, 10 and the cap member 33 is threadably engaged to the rearward end of the cylinder 11.

To retract the piston 13 rearwardly in the cylinder, the release lever 32 is pressed downwardly towards the cylinder and the rearward end of rod 14 is grasped and moved rearwardly. To dispense plastic material the release handle 32 is released to place the detent plate 29 in operation, and the handles on the outer arms of levers 15 and 16 are grasped in the hand of the operator and repeatedly squeezed to move them together. In each squeezing operation whereby the handles are moved towards each other, the feeding plate 29 moves the rod 14 forwardly in a sequence of increments, and the piston 13 is thus advanced to eject plastic material out through the nozzle 12. By reason of the pressure built up in the cylinder on the plastic material, the plastic material will tend to flow from the nozzle 12. In ending a dispensing operation the operator may desire to immediately cut off the flow of material from the nozzle. To obtain this quick cut-off, the release handle 32 is pressed downwardly toward the cylinder which causes the detent plate to release the rod 14 and allows the built-up pressure on the material in the cylinder to be released or dissipated, and the flow of material out of the nozzle is terminated. The positioning and relationship of the operating handle and the release handle is such that a quick change from dispensing material to a cut-off of the material may be readily effected with the one hand grasping the levers.

This description includes the disclosure contained in the appended claims which are incorporated by reference in this description.

Although my invention has been described with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In a dispensing gun for plastic material, said gun having a cylinder for holding said material, a piston in said cylinder for moving said material, and a piston rod extending axially of, and rearwardly from, said cylinder for reciprocating said piston, the improvement comprising in combination a feeding plate carried on said rod and adapted to frictionally grip and move said rod forwardly upon forward movement of the feeding plate and to free, and move relative to, said rod upon rearward movement of the feeding plate, a pair of bell-crank levers, said levers having inner arms extending toward each other and pivotally interconnected and having outer arms extending rearwardly of said gun and in hand-gripping relationship to each other whereby movement of said outer arms toward each other moves said inner arms forwardly, engaging

means carried by one of said inner arms and adapted to engage and forwardly move said feeding plate upon forward movement of said inner arms, a pivot mounting for each of said bell-crank levers, a pair of support members extending rearwardly from said cylinder and each carrying one of said pivot mountings at a position rearwardly of said cylinder, said pivot mountings being movable relative to each other upon movement of said bell-crank arms, anchoring means carried by said cylinder for securing the forward end of each said support member to said cylinder, resilient means for resiliently urging said feeding plate and inner arms in a rearward direction, a detent plate carried on said rod and adapted to frictionally grip and hold said rod against rearward movement upon rearward movement of the detent plate and to free, and move relative to, said rod upon forward movement of the detent plate, a releasing handle connected to said detent plate and disposed longitudinally of said gun, a pivot mounting for said detent plate, a support member extending rearwardly from said cylinder and carrying said pivot mounting at a position rearwardly of said cylinder, anchoring means carried by said cylinder for securing the forward end of said support member to said cylinder, and resilient means for resiliently urging said detent plate in a rearward direction, the arrangement of the feeding plate and detent plate being such that upon each movement of said outer arms toward each other the feeding plate moves the said rod forwardly free of said detent plate, and upon return movement of said outer arms away from each other the detent plate grips the said rod to maintain the advance gain made by said feeding plate.

2. In a gun for dispensing plastic material, said gun having a cylinder and a piston rod extending rearwardly therefrom, improved mechanism comprising in combination a feeding plate grippingly engageable with said rod for moving said rod in a forward direction, a pair of levers, said levers respectively having handle portions extending rearwardly of the gun and arranged to be moved toward each by hand gripping and having operating portions extending toward each other and pivotally interconnected, one of said operating portions being adapted to engage and forwardly move said feeding plate upon movement of said handle portions toward each other, a support member extending rearwardly from said cylinder for each said lever, said support members, respectively, providing fulcrum supports for said levers and being arranged to flex to accommodate movement of said interconnected levers relative to each other, a detent plate grippingly engageable with said rod for maintaining the gain in forward movement of said rod by the said feeding plate, a handle carried by the detent plate for moving the same to disengage the detent plate from said rod for release of said rod, a support member extending rearwardly from said cylinder for supporting said detent plate and arranged to permit angular movement of said detent plate relative to said rod, resilient means for resiliently urging said feeding plate to non-rod-gripping position and said detent plate to rod-gripping position, and a cap member adapted to be carried by said cylinder and engaging the forward end of each of said support members for securing the same in position.

3. In a gun for dispensing plastic material,

said gun having a cylinder and a piston rod extending rearwardly therefrom, a feeding plate for progressively advancing said rod forwardly and a detent plate for maintaining the advance of said rod, the improvement comprising in combination a cap member adapted to threadably engage the rear end portion of said cylinder, said cap member having a central opening for accommodating said rod and three spaced openings extending therethrough at radial distances from said central opening, three support members disposed substantially parallel to the axis of said cylinder and having their forward ends positioned in said openings, said openings and said forward ends having complementary interlocking portions adapted to interlock said support members to said cap member upon radially outward positioning of said support members in said openings, a spacer member positioned adjacent said cap member and intermediate said support members for holding said support members in radially outward position and interlocked with said cap member, a pair of operating crank-arm levers positioned on opposite sides of said rod and pivotally interconnected with each other at a position adjacent said rod, said levers being adapted to actuate said feeding plate, two of said support members being connected to said levers, respectively, to provide fulcrum support to said levers, said two support members being adapted to permit pivotal swinging of said levers relative to each other for actuating said feeding plate and to accommodate the lateral movement of the fulcrum supports of said levers toward and away from each other upon pivotal swinging of said levers relative to each other, and a releasing handle connected to said detent plate and carried by the third of said support members, said third support member being adapted to permit angular swinging of said detent plate relative to said rod.

4. In a gun for dispensing plastic material, said gun having a cylinder, a piston rod extending rearwardly of the cylinder, a pair of operating levers for advancing said rod, and a release lever for releasing said rod, an improved supporting structure for said operating levers and said release lever comprising in combination a cap member adapted to be threadably engaged to said cylinder at the rearward end thereof, said cap member having a central open space adapted to accommodate said rod and having three T-shaped openings spaced apart and extending through said cap member, the stem portions of said T-shaped openings, respectively, being directed radially outward, three support members extended rearwardly from said cylinder and disposed substantially parallel to the axis of said cylinder, the said support members having reduced portions adjacent the forward ends thereof, said reduced portions being formed to complementarily interengage in the stem portions of said openings for locking said support members against longitudinal movement relative to said cap member, a spacer member positioned rearwardly of, and next adjacent, said cap member, said spacer member having an open space for accommodating said rod, said spacer member having a peripheral boundary portion positioned adjacent said support members to hold the same in said stem portions of said openings to lock said support members to said cap member, means connecting two of said support members to said operating levers at a first distance from said cap member, and means connecting the third

of said support members to said release lever at a second distance from said cap member.

5. In a gun for dispensing plastic material, said gun having a cylinder and a piston rod extending rearwardly and axially of said cylinder, improved mechanism comprising a feeding plate for advancing said rod, a pair of crank-arm levers positioned at a distance from said cylinder and disposed on opposite sides of said rod, said 10 crank-arm levers having inner arms adapted to actuate said feeding plate and having outer arms providing handles movable relative to each other by hand gripping, a fulcrum support carried by said cylinder for each said lever for providing a fulcrum for each said lever at a distance from said cylinder, first means interconnecting said inner arms and providing for the simultaneous swinging movement of said inner arms in unison on said first means and relative to each other, and second means providing for limited lateral movement of said fulcrum supports relative to each other for accommodating the pivotal swinging of said levers on said fulcrums and on said first means.

6. In a gun for dispensing plastic material, said gun having a cylinder and a piston rod extending rearwardly from said cylinder, the improvement comprising in combination a feeding plate having an opening therethrough for accommodating said rod, said feeding plate being adapted to grip and advance said plate upon moving said feeding plate forwardly at a side of said rod, a collar member carried by said rod rearwardly of said feeding plate, a pair of crank-arm levers each having an inner arm and an outer arm, said inner arms being directed toward each other and said outer arms being directed in a rearward direction, pivot means pivotally connecting said inner arms to said collar member, 30 one of said inner arms extending to and beyond said rod to a position adjacent and rearwardly of said feeding plate at a side of said rod to engage the feeding plate, the said outer arms providing handles movable toward and away from each other, movement of said handles toward each other moving said one inner arm forwardly to move said feeding plate forwardly at a side of said rod, resilient means urging said feeding plate rearwardly and axially of said cylinder, support means carried by said cylinder for providing fulcrum support to said crank-arm levers at positions rearwardly of said cylinder and on opposite sides of said rod.

7. Improved operating mechanism for a plastic material dispensing gun having a cylinder and a piston rod extending axially and rearwardly of said cylinder, comprising in combination a feeding plate mounted on said rod for step-by-step advancing of said rod, a detent plate 55 mounted on said rod for retaining the gain of said rod as advanced by said feeding plate, a pair of handles disposed on opposite sides of said rod and extending rearwardly from said cylinder, said handles having portions cooperating to actuate said feeding plate for advancing said rod upon movement of said handles toward each other, a support member for each said handle, each support member being carried by, and disposed rearwardly of, said cylinder, said support members providing a fulcrum support for each said handle movable in a lateral direction to accommodate changes in the position of the respective fulcrums, another support member for said detent plate, said another support member being carried by, and disposed rearwardly

of said cylinder, said another support member providing a pivot support for said detent plate for swinging of said detent plate relative to said rod, a release handle carried by, and movable with said detent plate, said release handle being directed longitudinally of said rod toward said cylinder, and resilient means carried by said rod for urging said feeding plate and detent plate in a rearward direction.
